DOG COLLAR ORNAMENT OR SIMILAR ARTICLE

Daniel A. Klimkiewicz, Rutherford, N.J., assignor to Ronald A. Darby, Hawthorne, N.J.

Filed Sept. 23, 1965, Ser. No. 87,129

Term of patent 14 years

(Cl. D12—2)

FIG. 1

The broken lines in the drawing figures represent a fragmentary portion of the dog collar for illustrative purposes only.

I claim:

The ornamental design for a dog collar ornament or similar article, as shown and described.
